UNITED STATES PATENT OFFICE

JOSEPH RIDLINGTON, OF ACTON, LONDON, ENGLAND

HEAD LAMP FOR ROAD VEHICLES

Application filed July 20, 1928, Serial No. 294,239, and in Great Britain March 20, 1928.

This invention relates to supports for head lamps of road vehicles of the type which provides for the combined dipping and swivelling of the lamps by a single movement of a single lever, and it has for its object to permit of the lamps being dipped through their normal angle of dipping, i. e. the angle of dipping which will remove dazzle from on-coming traffic which is about 20 to 30 degrees, without any swivelling movement and then to cause the lamps to swivel during the remaining dipping movement. A further object of the invention is to provide for the swivelling of the lamps in either direction after the normal dipping has been effected without causing any further dipping movement.

According to the present invention the cams employed for imparting the swivelling movement to the lamps are mounted loosely on the transverse rocking shaft which carries the lamps so that they can be rotated independently of said shaft. Each cam consists of a drum in which are two inclined grooves with a short connecting straight or neutral groove said inclined grooves being arranged in opposite directions so that rotation of the cam in one direction will cause the lamps to be turned in one direction and rotation of the cam in the opposite direction will cause the lamps to move in the opposite direction. The length of the straight or neutral part of the groove of each cam is such as will allow the lamps to be dipped through their normal angle of dipping before the cam can be operated to swivel the lamps. The finger which engages the groove of the cam is carried by the lamp stem mounted in the adjacent socket in such a position that its axis passes through the centre of the rocking shaft. By coupling the stems carrying the two lamps together by means of suitable link-work a single cam may be employed. The cam is rotated by any suitable means which can be conveniently actuated by the driver of the vehicle from his seat, the preferred arrangement being by the rotation of the handle of the lever which operates the dipping mechanism.

To prevent any independent swivelling

movement being imparted to the lamps until they have been partially dipped a locking device is employed to secure the cam against rotation until the predetermined dipping movement of the lamps has been effected. A convenient form of the locking device comprises a pivoted lever carrying at one end a stud which is adapted to engage a hole, recess, or groove in the cam whereby its rotary movement will be prevented, and at the other end carrying a finger with which the lever, by which the rocking movement is imparted to the transverse shaft for dipping the lamps, engages, after the predetermined dipping movement has been imparted to the lamps, a suitable spring being employed to return the pivoted lever to bring it into locking engagement with the cam. Means may be provided for rendering this locking device ineffective during the running of the vehicle from the driver's seat, so that the lamps can be swivelled without being dipped.

In the accompanying drawings which illustrate this invention:—Figures 1 and 2 are views in side and front elevation respectively of the lamp carrier. Figures 3, 4 and 5, are views in side elevation, sectional front elevation and plan respectively of the preferred manipulating mechanism. Figure 6 is a developed view of the cam, and Figure 7 is a similar view of a modified form of cam.

Throughout the views similar parts are marked with like numerals of reference.

The brackets for supporting the lamps—not shown in the drawings—are carried by stems 1 which are mounted in sockets 2 carried by brackets 2* on the cross or transverse shaft 3. In the present construction as a single cam is employed the two stems 1 are coupled by arms and a link 4 and the cam 5 is arranged to operate one of said stems, the boss or finger 6 which engages the cam being carried by an arm 7 mounted on the stem 1 in the adjacent socket 2.

The cam 5 which is mounted loosely on the shaft 3 consists of a drum in which are two oppositely inclined grooves 5^a and 5^b with a short straight length of groove 5^c between them. For convenience in manufacture the

two grooves may be made as a single continuous groove as shown in Figure 7, said groove being made of a width slightly exceeding the diameter of the boss or finger 6 so as to allow the cross shaft 3 to be rotated through an angle of say 20 to 30 degrees before the cam will impart movement to the arm 7.

The desired rocking motion is imparted to the transverse shaft 3 by means of an arm 8 fixed on said shaft and coupled to the hand operating lever 9 by means of a rod or link 10 and a convenient mechanism for imparting a rocking motion to the cam 5 consists of an arm 11 carried by said cam which is coupled by means of a link 12 to an arm 13 carried by a rocking tubular shaft 14 mounted on the rod or link 10. Motion is imparted to this rocking shaft 14 by the rotation of a knob 9* at the upper end of the operating lever 9 which acting through a screw gear 15 imparts motion to a swinging arm 16 which is coupled to an arm 17 on the rocking shaft 14 by a link 18, the links 12 and 18 being connected to their respective arms by means of ball and socket or other type of universal joint. This mechanism is irreversible so that while the cam can be rotated by turning the knob 9* no movement of the cam can take place until a turning movement is imparted to said knob.

The positive locking device for preventing any swivelling movement being imparted to the lamps except until they have been partly dipped consists of a lever 19 pivoted on one of the supports 20 carrying the bearings of the transverse shaft 3 and carrying at its upper end a stud 21 which engages a slot 22 in the cam and of an offset arm 23 at the other end of the lever with which the arm 8 engages immediately after the end of the predetermined movement of the transverse shaft to produce the normal dipping of the lamps, a suitable spring 24 being employed to return the lever to bring it into locking engagement with the cam.

This device functions as follows:—If it is desired to dip the lamps through the normal angle of dip—during which no swivelling movement takes place—the lever 9 is simply pushed forward to the desired extent. If it is desired to swivel as well as dip the lamps the lever 9 is pushed further forward so that the arm 8 engages the arm 23 on the lever 19 and withdraws the stud 21 from engagement with the cam. The further dipping of the lamps will cause them to swivel in one direction but by rotating the upper part 9* of the lever 9 the cam can be independently rotated to swivel the lamps in either direction, and the lamps can be caused to swivel and dip simultaneously by the combined manipulation of the lever 9 and its knob 9*.

It will be appreciated that by this inven-

tion no swivelling movement can be imparted to the lamps until their dipping movement is substantially completed, and that after said dipping movement is completed independent swivelling movement can be imparted to the lamps in either direction, but should it be desired to independently swivel the lamps before any dipping movement has been imparted to them the cam locking device must be released, a means—such as a “Bowden wire” mechanism—must be employed to release the locking device and thereby free the cam. This can be effected either by moving the arm 23 out of the path of movement of the arm 8 or by withdrawing the stud 21 out of engagement with the slot 22 of the cam.

What I claim is:—

1. A mounting for head lamps of motor road vehicles comprising stems adapted to carry the lamps, a rocking shaft mounted in fixed bearings, sockets carried by said shaft in which said stems are mounted, a coupling between said two stems, a grooved cam loosely mounted on said shaft in juxtaposition to one of the lamp sockets, an arm fixed on the stem in the lamp socket adjacent to the cam and adapted to engage the groove in the cam, means for rocking the shaft, means for rotating the cam on said shaft, a device for locking the cam against rotation, and means for unlocking the cam immediately before the end of the movement of the rocking shaft to produce the complete dipping of the lamps.

2. A mounting for head lamps of motor road vehicles comprising stems adapted to carry the lamps, a rocking shaft mounted in fixed bearings, sockets carried by said shaft in which said stems are mounted, a coupling between said two stems, a grooved cam loosely mounted on said shaft in juxtaposition to one of the lamp sockets, an arm fixed on the stem in the lamp socket adjacent to the cam and adapted to engage the groove in the cam, means for rocking the shaft, means for rotating the cam on the shaft, a device for locking the cam against rotation, means for unlocking the cam immediately before the end of the movement of the rocking shaft to produce the complete dipping of the lamps, and means for controlling the cam locking device from the driver's seat.

3. A device for mounting head lamps of motor road vehicles comprising stem adapted to carry the lamps, a rocking shaft mounted in bearings carried by the chassis, sockets mounted on the shaft in which said stems are mounted, a coupling between said two stems, a hand lever for rocking said shaft, a grooved cam loosely mounted on said shaft in juxtaposition to one of the lamp sockets having two inclined grooves with a short connecting straight groove, means mounted on the lever for rocking the shaft for rotating the cam on said shaft, an arm fixed on the stem in the lamp socket adjacent to the cam and

adapted to engage the groove in the cam, a device for locking the cam against rotation, and means for automatically unlocking the cam before the end of the movement of the rocking shaft to produce the complete dipping of the lamps.

4. A device for mounting head lamps of motor road vehicles comprising stems adapted to carry the lamps, a rocking shaft mounted in bearings carried by the chassis, two sockets carried by the shaft in which said stems are mounted, a coupling between said two stems, a hand lever for rocking said shaft, a grooved cam loosely mounted on said shaft in juxtaposition to one of the lamp sockets having two inclined grooves with a short connecting straight groove, means mounted on the hand lever for rotating the cam on the shaft, an arm fixed on the stem in the lamp socket adjacent to the cam and adapted to engage the groove in the cam, a locking device for fixing the cam against rotation, and means for controlling the cam locking device from the driver's seat.

JOSEPH RIDLINGTON.
